UNITED STATES PATENT OFFICE.

JAMES DALTON, OF LOS ANGELES, AND BERNARD C. DE MEULLE, OF LONG BEACH, CALIFORNIA, ASSIGNORS TO DALTON OVEN CO., A COPARTNERSHIP COMPOSED OF JAMES DALTON AND BERNARD C. DE MEULLE, OF LONG BEACH, CALIFORNIA.

DESIGN FOR A REEL-OVEN.

54,067.

Specification for Design.

Patented Nov. 4, 1919.

Application filed July 5, 1919. Serial No. 309,235. Term of patent 14 years.

To all whom it may concern:

Be it known that we, JAMES DALTON, a citizen of the United States, residing at Los Angeles, in the county of Los Angeles and State of California, and BERNARD C. DE MEULLE, a subject of the King of Great Britain, residing at Long Beach, in the county of Los Angeles and State of California, have invented a new, original, and ornamental Design for a Reel-Oven, of which the following is a specification, reference being

had to the accompanying drawing, forming part thereof.

The drawing is a perspective view of an oven embodying our new design.

We claim:

The ornamental design for a reel oven, as shown.

JAMES DALTON.
BERNARD C. DE MEULLE.

Witness:

LOUIS W. GRATZ.
